H. A. DOUGLAS,
CURRENT CARRYING PLUG.
APPLICATION FILED OCT. 14, 1918.

1,347,738.

Patented July 27, 1920.

UNITED STATES PATENT OFFICE.

HARRY A. DOUGLAS, OF BRONSON, MICHIGAN.

CURRENT-CARRYING PLUG.

1,347,738.

Specification of Letters Patent. Patented July 27, 1920.

Original application filed February 4, 1918, Serial No. 215,330. Divided and this application filed October 14, 1918. Serial No. 258,065.

To all whom it may concern:

Be it known that I, HARRY A. DOUGLAS, citizen of the United States, residing at Bronson, in the county of Branch and State 5 of Michigan, have invented a certain new and useful Improvement in Current-Carrying Plugs, of which the following is a full, clear, concise, and exact description.

My invention relates to current carrying 10 plugs. It is one object of my invention to provide a given plug for the reception of a terminal conductor or conductors passed into the plug either from end to end of the plug or through a side of the plug and thence toward one end of the plug. This 15 feature of my invention may be practised in conjunction with a so-called double pole plug, or a single pole plug.

In carrying out this feature of the invention I provide a plug with one bore, if the 20 plug is a single pole plug or two bores if the plug is a double pole plug, such bore or bores extending longitudinally through the plug. There is also provided one or two 25 bores, as the case may be, which communicate with the aforesaid bore or bores and extend laterally into the plug. The longitudinally disposed bore or bores are thus 30 always in service in whole or in part whether the conductor or conductors are passed into the plug longitudinally or laterally thereof, the lateral bores not being 35 used, as the invention is preferably practised, when the conductors extend from end to end of the plug.

In accordance with another feature of the invention the plug is divided lengthwise into sections, a half of each bore, or the bore 40 if there is but one, being formed in each section of the plug. Where the plug is formed in sections it is desirably provided with a sheath for maintaining the sections in assembly.

This plug is usually to be coupled with a 45 socket. The plug of my invention has been used as an element distinct from the plug portion or base of an incandescent lamp to include such lamp in circuit but I do not wish so to limit the plug of my invention.

50 I will explain my invention more fully by reference to the accompanying drawing showing the preferred embodiment thereof and in which Figure 1 is a view, in longitudinal section, illustrating a connector having a shell and plug equipped in accordance

with my invention, one of the two arrangements of conductors being shown in conjunction with the plug, a lamp being shown in elevation within the shell; Fig. 2 is a view on line 2—2 of Fig. 1; Fig. 3 shows 60 another disposition of conductors within the plug of the connector; Fig. 4 is a view in elevation of the structure as it appears in Fig. 3; Fig. 5 is a view in plan of the rear part of the shell appearing in Fig. 4; Fig. 65 5^a is a view of the shell as it appears in Fig. 5 minus the retaining spring; Fig. 6 is a view in perspective showing the two parts of the core of the plug in separated relation; and Fig. 7 shows in perspective the 70 sheath that I prefer to employ for the plug when it is used as illustrated in Fig. 1.

Like parts are indicated by similar characters of reference throughout the different figures.

The shell 1 of the connector is preferably 75 metallic. Its front end is provided with bayonet slots 2 adapted to receive the bayonet pins 3 that project laterally from the base or plug portion 4 of the incandescent 80 lamp 5. The filament 6 of the lamp is connected with the contacts 7 and 8 that are provided upon the base or plug portion of the lamp. Both of these contacts are shown as being upon the inner end face of the 85 lamp base inasmuch as the connector illustrated is a so-called two pole connector, but to which type of connector the invention is not to be limited. A contact carrier 9, of insulating material, is fixedly located in the 90 mid portion of the shell. Metallic spring barrels 10 and 11 are secured to and pass through the contact carrier 9. Coiled springs 12 and 13 are located within the 95 spring barrels. These coiled springs press the contact plungers 14 and 15 forwardly to have them respectively engage the contacts 7 and 8 upon the lamp base. These same springs press the contact plungers 16 and 17 rearwardly to engage them with contacts 18 and 19 that are suitably connected with the terminals of a source of current 100 through the intermediation of flexible conductors 20 and 21.

The contacts 18 and 19, the conductors 20 105 and 21 leading to these contacts, and the coverings or serving for these conductors are disposed within and are carried by a contact carrying plug of insulating material, which contact carrying plug is preferably 110

divided longitudinally into sections by being symmetrically formed into halves 22-23 as illustrated in Fig. 6. Two cylindrical bores 24, 25 extend longitudinally through the contact carrying plug 22-23, a half of each bore being formed in each half of said contact carrying plug. Transversely extended bores 26, 27 merge with the bores 24, 25, the inner ends of the bores 26, 27 being curved 10 forwardly to be tangential to and thereby merge gradually with the other bores. A half of each of the bores 26, 27 is formed in each half of the contact carrying plug 22-23. When the conductors 20, 21 extend into 15 the plug 22-23 laterally of such plug the sheath 28, clearly illustrated in Fig. 7, is employed, the bore of this sheath being equal in diameter to the diameter of the plug whereby the two halves of the plug are prevented 20 from slipping transversely of the sheath. The rear ends of the plug halves 22, 23 abut against the rear end wall 29 of the sheath 28. The forward end of the sheath is turned inwardly, as indicated at 25 30 in Fig. 1, to engage the front ends of the plug halves 22, 23. The two halves of the plug are thus prevented from slipping endwise with respect to each other. A ferrule 31 incloses the conductors 20 and 21 and a 30 tube 32 through which these conductors are led. This ferrule has a head or flange 33 that is located within the interior of the sheath 28, said ferrule projecting into this sheath through the slot 34 that is formed 35 longitudinally of the sheath 28 to permit the ferrule to be slipped into the sheath from the front end thereof. The flange prevents lateral withdrawal of the ferrule. In the arrangement illustrated in Fig. 1 40 the conductors 20 and 21 first pass through the bores 26, 27 before passing into the bores 24, 25. In the arrangement illustrated in (Figs. 3 and 4, the conductors project through the rear end of the contact carrying plug 22-23 extending throughout the entire length of the bores 24, 25 and passing through no part of the bores 26, 27. In this arrangement the ferrule 31 is omitted and the sheath 28' is minus the longitudinal slot 45 34 but has its rear end open as indicated at 35 in order that the conductors may pass from the plug. To maintain the conductors 20, 21 and their terminal contacts 18 and 19 in assembly with the contact carrying plug 50 22-23, I provide said contacts with flanges 35, 36 that are received within the annular enlargements 37, 38 of the bores 24, 25. The sheath of the plug 22-23, whether of the form illustrated in Fig. 1 or of the 55 form illustrated in Fig. 3, is provided with bayonet pin extensions or projections 39 receivable within bayonet slots or channels 40 provided in the rear end of the shell 1. Instead of relying upon the contacts 16 and 60 17 to maintain the bayonet pins 39 in their

seats within the bayonet slots 40 I provide a strip or wire retaining spring 41 extending laterally of the shell and disposed in the zone of the bayonet slots 40 and which retaining spring has an arrangement that is 70 well illustrated in Figs. 2, 3 and 5, this feature being claimed in my original application Serial No. 215,330, filed February 4, 1918, of which the present application is a division. This spring is depressed at its 75 intermediate portion 41' to contact with the sheath 28 or 28' of the plug, this depressed portion being received in the transverse slot or opening 42 and being substantially co-extensive with this slot to have abutting engagement at the ends of the slot where the spring rises to have its sections 41² engage the exterior of the shell 1. The ends of the retaining spring are depressed to enter the bayonet slots 40 and engage the sheath 28 80 or 28', these spring ends extending across the entrance branches of the bayonet slots 40 to be engaged by the bayonet pins 39. When the plug 22-23 is inserted the bayonet pins 39 engage the spring 41 and flex it longitudinally of the shell from its normal plane, this plane being resumed by the spring when the bayonet pins are in their seats owing to the resilience of the spring and the substantially fixed anchorage of the spring at its 85 mid portion to the shell, the ends of the spring 41 serving to hold these bayonet pins in their seats. Any preferred means may be employed for holding the spring 41 in assembly with the shell 1. In the preferred 1 embodiment of the invention two ears 43 are struck up from the shell where the mid portion 41' of the spring is received and are lapped over this intermediate portion 1 of the spring to hold the spring in the assembly illustrated clearly in Fig. 2. These ears 43 serve to coöperate with the contiguous portions of the shell and also with the underlying sheath normally to hold the spring in its plane, the engagement of the spring 1 and shell being sufficiently firm to establish a substantially fixed relation between the mid section 41' of the spring with the shell so that the spring is merely permitted to yield, due to its own resilience, when the 1 plug 22-23 is being inserted within or removed from the shell. The ends of the spring are depressed into the bayonet slots to engage the sheath of the plug and thereby have full effective engagement with the bayonet pins. While the spring 41 is shown for the purpose of holding the plug in assembly with the shell it is obvious that it is not limited to the nature of the contact carrier that it serves to hold in position.

While I have herein shown and particularly described the preferred embodiment of my invention I do not wish to be limited to the precise details of construction shown as changes may readily be made without de-

parting from the spirit of my invention, but having thus described my invention I claim as new and desire to secure by Letters Patent the following:—

A current carrying plug having a bore extending thereinto laterally and toward one end of the plug, in combination with a conductor extending into the plug through said bore, a sheath for the plug provided

with a longitudinal slot through which the 10 conductor is passed, and a ferrule surrounding said conductor and projecting into the sheath through said slot and having a flange within the interior of the sheath to prevent lateral withdrawal of the ferrule. 15

In witness whereof, I hereunto subscribe my name this 24th day of Sept. A. D., 1918.

HARRY A. DOUGLAS.
